Primary Examiner — Sheryl Lane*Assistant Examiner* — Aula Soroush(74) *Attorney, Agent, or Firm* — Panasonic IP Management; Kerry S. Culpepper(57) **CLAIM**

I claim the ornamental design for a nozzle for oral waterjet, as shown and described.

DESCRIPTION

FIG. 1 is a front perspective view of a nozzle for oral waterjet of the present invention;
FIG. 2 is a front view thereof;
FIG. 3 is a rear view thereof;
FIG. 4 is a first side view thereof;
FIG. 5 is a second side view thereof;
FIG. 6 is a top view thereof;
FIG. 7 is a bottom view thereof; and,
FIG. 8 is an end view of the sectioned part taken along the line 8-8 in FIG. 2.

(Continued)

The broken lines in the drawings represent portions of the nozzle for oral waterjet that form no part of the claimed design.
